UNITED STATES PATENT OFFICE.

PIO CACCIA, OF NEW YORK, N. Y.

FERMENTATION TUBE.

Application filed September 8, 1925. Serial No. 55,168.

This invention relates to improvements in 5 fermentation tubes, and has for its object the provision of an apparatus accurate and rapid in operation, yet exceedingly simple in construction.

The invention comprises further features and combination of parts, as hereinafter set forth, shown in the drawing and claimed.

In the drawing is shown an elevation of 10 the apparatus embodying features of invention.

Referring now in particular to the accompanying drawing, the apparatus comprises essentially a tube A connected to a bulb O by means of an angularly disposed neck portion, and supported on the base portion p. Arranged coextensively with said tube A is a pipette B, which latter is rigidly connected to said tube A by means of the supports m 20 and n, and further has its lower end flexibly connected to a receptacle C through the medium of a rubber tube S.

The upper ends of said tube A and pipette B are joined by glass tube sections s and r 25 carrying a two-way cock D from which latter is directed another tube section t leading to other apparatus (not shown). By this arrangement it is obvious that open communication between said tube A and pipette B may be established by the manipulation of said cock D, or communication may be established direct from the pipette B through the sections s and t to other apparatus, as above referred to.

In the operation of the apparatus a quantity of 5N NaOH is placed in the receptacle C, which latter is elevated until the liquid passes into the graduated pipette B. When the NaOH solution reaches the cock D, the latter will be closed and the receptacle C placed upon a suitable support.

A quantity of the liquid (10 cc.), the sugar content thereof having been previously determined, will be poured into the bulb O, whereupon a slight inclination of the apparatus will cause said liquid to flow into the tube A, thereby forcing out the air. Due to the atmospheric pressure the fluid does not flow back into the bulb O, and upon adding a very small quantity of metallic mercury into the opening in the bulb O, said angularly disposed neck portion will be sealed, thus forcing the carbon dioxide

formed to pass to the top of said tube A, the liquid in the meantime being forced back 55 into the bulb O. The receptacle C, having been placed under the level of O, the cock is opened thus permitting the gas collected in the top of said tube A to flow into the graduated pipette B by suction. It will, of course, be understood that the opening of the cock D will tend to siphon the liquid in O to the receptacle C. However, the gas which is at the top of tube A passes into B 60 due to the siphon effect above referred to and is absorbed by the liquid in B, (NaOH), which latter is attempting to reach the receptacle C.

If other gases are present, the cock D is manipulated to connect the tube sections s 70 and t, which latter will be connected with other gas apparatus for a complete analytical examination, as aforesaid. As we know the volume of CO_2 absorbed by the NaOH we can determine the quantity of sugar contained in the liquid tested. When the amount of CO_2 formed becomes known, the amount of sugar present in the original solution is calculated as follows:

The theoretical yield of carbon dioxide 80 from glucose, according to the equation:

is 48.88 per cent. The weight of CO_2 obtained during the fermentation multiplied 85 by the factor 2.2 will give the amount of fermentable sugar present. The process in the fermentation method of estimating sugars is to estimate the carbon dioxide by 90 measuring the volume of gas: 1 cc. of evolved carbon dioxide corresponds to 1.96 mgs. carbon dioxide or about four mgs. of sugar. During fermentation other gases are evolved 95 which are not absorbed by the NaOH and will remain at the top of B. These gases can be taken out and determined with other apparatus as pointed out hereinbefore.

I claim:

1. Apparatus of the class described, comprising in combination, a tube, a bulb integral with said tube, disposed angularly therewith and in communication with said tube, a graduated pipette disposed coextensive with said tube, means effecting communication therebetween, and a receptacle

flexibly connected to the bottom of said pipette.

2. Apparatus of the class described, comprising in combination, a vertical tube, an angularly disposed bulb integral therewith and in communication with said tube, a graduated pipette disposed coextensive with said tube, means effecting communication

therebetween consisting of tube sections and a two-way cock, a tube section connecting said pipette to other chemical apparatus through the manipulation of said cock, and a receptacle in communication with said pipette by means of a flexible tubing. ¹⁰
